UNITED STATES PATENT OFFICE

JOHN W. WHITE, OF BARBERTON, OHIO, ASSIGNOR TO SEIBERLING RUBBER COMPANY,
OF BARBERTON, OHIO, A CORPORATION OF DELAWARE

BAND BUILDING MACHINE

Application filed August 7, 1929. Serial No. 384,195.

This invention relates to machines for making bands out of strips of flexible material, and particularly such bands as are adapted for shaping and incorporation in 5 pneumatic tire casings.

One object of my invention is to provide an apparatus whereby a strip of material such, for example, as cushion gum for a tire band, may be accurately and quickly 10 wrapped upon a drum, or upon fabric already applied to the drum, in the exact length required.

A further object is to apply the strip material smoothly, without wrinkles. Still 15 further objects are to provide improved means for feeding and severing the material and for automatically connecting and disconnecting a driving device with the material feeder by the act of moving said feeder 20 into and out of its operative position.

Of the accompanying drawings, Fig. 1 is 25 a front and right-side perspective view of a band-building machine embodying my invention in a preferred form.

Fig. 2 is rear and right-side perspective view.

Fig. 3 is a longitudinal, vertical section showing the work and some of the principal parts of the machine.

Fig. 4 is a detail longitudinal section of the driving clutch.

Referring to the drawings, 10 is a base having an upright frame standard or column 11 mounted thereon and 12 is a horizontal branch or bar projecting from said column and carrying at its end a bearing 13 for detachably receiving the shaft or spindle 14 of a cylindrical building drum 15. The drum has an internal ring, spokes and hub 40 forming a spider 16 to which the shaft is secured. Said shaft turns freely in its bearing 13 so that the drum may be rotated either by the operator's hands or mechanically by a feed-roller to be described.

On a horizontal fixed shaft 17 projecting from the column 11 is pivoted a rectangular frame 18 at the forward end of which is journaled a feed roller 19. Pivotal movement is imparted to the frame 18 for the purpose of 50 raising the roller 19 away from and lower-

ing it onto the drum by means of a pedal lever 20 pivoted on the base 10 and connecting with the rear end of the frame 18 by means of a thrust-rod or link 21. The rear end of the pivoted frame is overbalanced so as normally to hold the feed roller away from the drum by means of a counter-weight mounted on a cross-platform 22 connecting the side bars of the frame, the said counter-weight consisting mainly of an electric motor 23 for driving the feed roller.

The feed roller 19 is driven by means of a belt 24 passing around one end of the roller and over a pulley 25 attached to a counter-shaft 26 which is mounted in a bearing on a frame plate 27 alongside of the motor. The shaft carries a worm gear 28 meshing with a worm 29 on a longitudinal shaft 30 which is rotated from the shaft of motor 23 through a pulley 31 on the motor shaft, a belt 32 and a pulley 33 on shaft 30. Pulley 33 is loosely mounted on the end of shaft 30 and is formed with one member of a friction clutch, namely a friction facing 34 which coacts with a complementary clutch-plate or flange 35 fixed to the shaft 30.

The electric motor 23 is constantly operated while the machine is in use, and provision is made for automatically connecting it in driving relation to the shaft 30 so as to propel the feed roller 19 through the intermediate driving connections, by the act of the machine operator in depressing said roller upon the drum 15 through the tilting of the frame 18 by means of pedal lever 20. Said provision consists of a clutch-operating lever 36 pivoted at 37 on the plate 27 and formed at its outer end with a transverse projection 38 engaging a rounded central boss 39 on the pulley 33, the inner end of said lever having an upturned projection 40 adapted to press against a fixed plate 41 carried by a structure on the column 11, there being an adjustable thumb-nut 42 mounted on a fixed screw 43 passing through a hole in the lever projection 40 to act as a back-stop for turning the lever in a clutch-releasing direction. It will be evident that the downward tilting of the forward end of the frame 18 raises its rear end together with the fulcrum of lever 95 100

36, thus moving forwardly the end projection 40 of said lever which is positioned above the pivot-rod 17 of the frame, so that the lever will be turned back and the projection 38 on its rear end will engage the friction clutch and set in motion the driving mechanism of roller 19, while the reverse action of lifting the forward end of frame 18 automatically disconnects the drive.

10 In the combination including these automatic parts, and in the combination including the liner-feeding devices to be later described, any suitable equivalent for the drum 15 as a band supporting means may be employed.

44 is a roll of fabric liner 44^a with which is interwound a thin strip or sheet 45 of cushion gum stock for incorporation in the band which is being built upon the drum 15.

20 The core bar 46 of said roll is removably fitted over a squared shaft 47 mounted to turn in a bearing held between a pair of blocks 48, 49, the former of which is strapped to the upper end of column 11 and the latter secured to the former by means of bolts 50.

25 A cylindrical extension 51 of shaft 47 forms a brake drum for said shaft which is engaged by the walls of a V notch in a brake shoe 52 pivoted to the block 49, the pressure of said 30 shoe being regulated by a screw 53 threaded in a plate 54 and having a winged head 55 at its outer end for turning it, whereby an adjustable friction may be imposed upon the shaft of roll 44 to determine the tension on 35 the liner 44^a.

Supported by the blocks 48, 49 below the shaft 47 is an anti-friction bearing 56 which carries the shaft 57 of a liner rewind roll 58 whose core 59 is slipped over said shaft.

40 That portion of the liner 44^a proceeding downwardly from the roll 44 and in a bight around the rewind roll 58 serves to turn the latter and wind up the liner after the gum strip 45 has left it.

45 For severing the gum strip 45, I provide a rocking snubber plate 60 formed with a guide slot 61 through which the liner and gum strip pass from the rear or below as indicated in Fig. 3. The ends of the snubber 50 plate are journaled in the side bars of an auxiliary or secondary frame 62 pivoted at 63 on the frame 18 and having a pair of coil springs 64 adapted to engage the side bars of frame 18 at their forward ends, to yieldingly transmit the downward pressure of auxiliary frame 62 to the pivoted frame 18.

55 The left-hand journal of snubber plate 60 has affixed thereto an arm 65 connecting by a link 66 with an arm 67 affixed to a rock-shaft 60 or handle bar 68 which has a pair of hand grips 69 thereon, said rock-shaft being journaled on the auxiliary frame. 70 is a liner guide roll mounted to turn freely on a fixed cross-shaft 71 supported at its ends by the 65 side bars of the auxiliary frame.

In building tire bands on this machine, the operator is supplied with strips of carcass fabric which are placed alongside of the machine within convenient reach, and these strips are successively taken and wrapped 70 around the drum and the ends spliced to make a band or tube, while the drum is turned by hand. The drum being of predetermined diameter suited to the particular band which is being made, said band will have the exact 75 desired length and the same will be true of each of its component layers. Over certain of the fabric layers, it is desirable to apply a narrower strip of thin sheet rubber or cushion gum, such operation being performed by 80 the present machine. Such a gum strip could also be laid on the drum before the laying of the first fabric ply, if desired. The fabric layers have their threads running diagonally in opposite directions in adjacent layers as 85 usual, and successive layers may have their edges stepped in to facilitate later bead formation at the edges. The drum may have circumferential marks thereon to aid in accurately positioning the fabric, and the liner 90 may be laterally shifted to center the gum strip properly as it is led onto the drum.

The parts being in the positions indicated in Fig. 1, the operator grasps the handlebar 68 to depress the auxiliary frame 62 and cause it to exert a yielding pressure on the pivoted frame 18 through the medium of the springs 64. By stepping on the treadle lever 20, the frame 18 is tilted to bring the feed roller 19 down upon the drum and to connect 100 the motor 23 with the roller-driving mechanism through the friction clutch 34, 35. In drawing down the auxiliary frame 62, the shaft 68 will at the same time be turned forward by means of the hand grips 69 to straighten the slot in the snubber plate 60 and permit the feeding of the liner 44^a and gum strip 45. The gum strip tends to leave the liner and follow around the feed roller 19 and may, if necessary, be started around by 110 hand. Both the drum 15 and the liner guide roll 70 are driven by the feed roller 19 through the medium of the intervening sheet material, and the feeding pressure may be adjusted to the exact degree required by 115 pressure of the operator's hands on the rock-shaft 68 transmitted through the auxiliary frame 62 and the springs 64 to the tilting frame 18. This arrangement and mode of 120 operation permits the gum strip 45 to be evenly and smoothly wrapped and rolled upon the drum 15 and caused to adhere to the adjacent ply of fabric without wrinkles or the pocketing of air, the results being much superior to those attained with a positively-driven underlying drum or roller.

When one wrap of the gum strip is nearly complete, the operator rotates the rock-shaft 68 by means of the grips 69 in a backward direction to turn the snubber slot cross-wise 120

as indicated in Figs. 1 and 3 and arrest the feed of the liner 44^a; raises the auxiliary frame to discontinue the pressure of roller 70 on roller 19, and turns it back to the position shown in Fig. 1.

5 The continuing forward movement of the gum strip in response to the feeding action of the roller 19 causes said strip to be broken off from the part remaining on the liner, at 10 a point in the rotation of the drum judged by the operator to be sufficient to complete the wrap with a small margin for a lap splice. The pressure of roller 19 may be continued long enough to complete and roll 15 down the wrap, after which the pedal 20 is released to allow the frame 18 and feed roller 19 to resume their inoperative positions and automatically disconnect the feed drive. Then, if desired, further wrappings 20 of fabric and gum strip may be applied in like manner until the tire band has been built up with the desired number of plies. The liner 44^a will be propelled by the guide-roll 70 during the operation of the machine and 25 rewound in the roll 58 through the driving action of the antecedent bight of the liner in the manner indicated.

After the tire band is completed, the drum 15 with the band thereon is removed from 30 the machine by slipping its shaft 14 out of the bearing 13 and carried to a tire-building machine to be transferred onto the drum of the latter, but this feature is not claimed as a part of my invention.

It will be understood that the described 35 embodiment is capable of rather wide variation without departing from the principles of my invention as defined in the claims.

I claim:

40 1. In a band-building machine, the combination of a freely rotatable band-sizing and building drum, a power-driven feed roller, means for supporting a roll of liner and sheet gum in position to be led over 45 said feed roller to apply the sheet to the drum or to material thereon, whereby also the drum is rotated from the feed roller through the liner and gum sheet, and a liner rewinder.

50 2. In a band-building machine, the combination of a freely rotatable band-sizing and building drum, a power-driven feed roller mounted for movement toward and from said drum for applying material to 55 and rotating the drum, and means for supporting a roll of material in position to be led to and around said feed roller.

3. In a band-building machine, the combination of a rotary building drum, a pivoted frame, a feed roller carried by the swinging movement of said frame into and out of coaction with said drum, means also carried by the frame for rotating the feed 60 roller, and means for supplying strip ma-

terial to said feed roller for application by it to the drum.

4. In a band-building machine, the combination of a freely rotatable building drum, a feed roller mounted for positioning movement toward and away from said drum for driving the latter and applying strip material thereto, and means automatically controlled by the positioning movement of said roller for applying a rotating force to the roller when it is moved toward the drum and removing said force when it is moved away.

5. In a band-building machine, the combination of band-supporting means, a coacting feed roller, a pivoted frame carrying said roller, drive mechanism carried by the frame for rotating said roller, a motor carried by said frame and connecting with said drive mechanism through a friction clutch, and means operated by the tilting of said frame for actuating said clutch when the frame is moved to carry the roller toward the band-supporting means, and releasing it when moved in the opposite direction.

6. In a band-building machine, the combination of band-supporting means, a coacting power-driven feed roller, means for supplying strip gum on a liner to said feed roller for application to a band on said supporting means, and a guide roller driven by said feed roller through the gum strip and liner for propelling and guiding the liner during its separation from the gum strip and after it leaves the latter.

7. In a band-building machine, the combination of band-supporting means, a strip feed roller coacting therewith, adjustable supporting means for said roller to move it into and out of operative relation with said band-supporting means, a liner guide roller coacting with the feed roller, and a support for said guide roller adjustable to press said rollers into coaction with each other and the feed roller into coaction with the band-supporting means.

8. In a band-building machine, the combination of band-supporting means, a coacting strip feed roller, an adjustable frame carrying said roller, a secondary frame adjustably mounted on said roller frame, a liner guide roller carried by the secondary frame and coacting with said feed roller, and a yielding connection between said frames.

9. In a band-building machine, the combination of band-supporting means, a pivotal frame, a power-driven strip feed roller carried by said frame for driving the band-supporting means, a secondary frame pivoted on the first-said frame, and a liner guide roller carried by said secondary frame and adapted to be driven by said feed roller.

10. In a band-building machine, the combination of a freely rotatable building

drum, a pivoted frame, a feed roller mounted on said frame above the drum for rotating the latter, roller driving mechanism mounted on said frame, means for supplying strip material in a liner to said feed roller, a liner guide roller adapted to be driven by said feed roller, a secondary frame pivoted to the first-said frame and carrying said guide roller, and rewinding means 10 for receiving the liner from said guide roller.

11. In a band-building machine, the combination of band-supporting means, means for supplying gum strip material in a liner to said supporting means, and snubbing means for arresting the liner to sever the gum strip material.

12. In a band-building machine, the combination of band-supporting means, means for supplying thereto gum strip material 20 in a liner, a slotted snubbing guide for the liner and gum strip material, and means for rocking said snubbing guide to arrest the liner and sever the gum strip material.

13. In a band-building machine, the combination of band-supporting means, a co-acting strip feed roller movable toward and away from said means, a liner guide roller, a pivoted frame carrying said guide roller for moving it into coaction with the feed 30 roller and the latter into coaction with the band-supporting means, and a rocking snubber mounted on said frame for arresting the liner and severing the strip material.

14. In a band-building machine, the combination of a freely rotatable building drum, a pivoted frame, a power-driven strip feed roller carried by said frame, for rotating the drum, means for supplying strip material in a liner to said roller, a liner rewinding device, a liner guide roller adapted to be rotated by said feed roller, a secondary frame pivoted to the first-said frame and carrying said guide roller, a snubber journaled on said secondary frame for arresting 40 the liner and severing the strip material, and a rockable handle-bar journaled on said secondary frame for moving the frames to bring the guide roller into coaction with the feed roller and the latter into coaction with the drum and having connections for turning 50 said snubber.

15. In a band-building machine, the combination of a freely-rotatable band-sizing and building drum, means for applying a 55 gum strip to said drum and rotating the latter through the interposed strip, and strip-supporting means driven by the gum-applying means through the interposed strip for carrying the strip to and applying it upon said gum-applying means.

16. In a band-building machine, the combination of a freely-rotatable band-sizing and building drum, a power-driven feed roller for applying a gum strip to said drum 60 and rotating the latter through the inter-

vening strip, and means including a mating roller driven by said feed roller through the intervening strip, a liner and gum-strip supply roller, and a liner rewind roller spaced from said mating roller for leading a 70 liner and gum strip to said feed roller and applying the strip upon the latter and for then returning the liner around said mating roller to the rewind roller.

In witness whereof I have hereunto set my hand this 12th day of July, 1929.

JOHN W. WHITE.
